Fig.3.

Fig.4.

Fig.5.

Fig. 6.

Fig. 7.

FIGURE 1 is a front perspective view of the control switch unit for emergency vehicles embodying my new design;

FIGURE 2 is a front view thereof;

FIGURE 3 is a view of the side not seen in FIGURE 1;

FIGURE 4 is a rear view thereof;

FIGURE 5 is a cross sectional view taken on the plane of the line 5—5 in FIGURE 2.

FIGURE 6 is a front, top and right side perspective view; and

FIGURE 7 is a front, bottom and right side perspective view thereof.

The dominant features of my design reside in those portions thereof shown in full lines.

I claim:

The ornamental design for a control switch unit for emergency vehicles, as shown and described.
